UNITED STATES PATENT OFFICE.

EDWARD H. FRICKEY, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

PULVERIZER.

1,037,232.

Specification of Letters Patent. Patented Sept. 3, 1912.

Application filed June 9, 1910. Serial No. 565,949.

To all whom it may concern:

Be it known that I, EDWARD H. FRICKEY, a citizen of the United States, residing at St. Louis, Missouri, have invented a certain 5 new and useful Improvement in Pulverizers, of which the following is a full, clear, and exact description, such as will enable others skilled in the art to which it appertains to make and use the same, reference being had 10 to the accompanying drawings, forming part of this specification, in which—

Figure 1 is a side elevational view of my improved pulverizer partly in vertical section. Fig. 2 is an end elevational view 15 partly in vertical section. Fig. 3 is a top plan view partly in horizontal section.

This invention relates to a new and useful improvement in pulverizers, and more particularly to the means for adjusting the 20 grinding surface with respect to the hammers or beaters.

This invention consists in the construction, arrangement and combination of the several parts, as will hereinafter be described and pointed out in the claims.

In the drawings, 1 indicates a casting which is preferably anchored to suitable timbers 2 constituting the foundation or support. This casting constitutes a casing, 30 in the peripheral wall of which are arranged two manhole plates 3 by which access may be gained to the interior. The outer part of the casting is provided with an opening, in which is arranged a removable casting 5 35 constituting a support for a screen frame 5 containing a wire mesh covering the discharge opening.

6 indicates a flanged ring coöperating with the screen frame to hold same in its 40 seat, said ring in turn being held in position by blocks 7 adjustably secured in position by means of threaded bolts 8, said blocks being loosely mounted on said bolts 8 so that by turning the screws 9 the inner ends of 45 said blocks may be forced downwardly to tighten the clamping ring 6 in position.

10 is the discharge spout, which is preferably connected to an exhaust fan or blower.

50 To renew the screen, it is only necessary to loosen the bolts 9, to swing the blocks 7 on the bolts 8 and raise the flanged ring 6, whereupon the screen may be removed. If

necessary, the pipe 10 may also be raised for the same purpose. The casting 4 which supports the screen frame is mounted to move in vertical guideways and provided with ribs 11 fitting in said guideways, said ribs having their lower ends beveled, as shown in Fig. 2.

55 12 is a bar having a beveled inner end to coöperate with the ribs 11, whereby, when clamping ring 6 is not firmly secured in position, the bar 12 may be adjusted inwardly and outwardly to adjust the screen with relation to the paths of travel of the revolving beaters by means of bolts 12^a secured in the casing. Bar 13, having a vertical inner face, is also made adjustable inwardly and outwardly by means of a threaded bolt 13^a secured in the casing for clamping the screen in its vertically adjusted position. Bars 12 and 13 are duplicated on each side of the screen, the bars 12 serving to support the casting 4 and its carried screen, 60 while the bars 13 serve to clamp the same in position. The clamping blocks 7 force the flanged screen and associate parts downwardly. To adjust the screen downwardly, it is only necessary to loosen the bolts 12^a, to 65 move the bars 12 outwardly, and tighten the clamping blocks 7. To adjust the screen upwardly, the clamping blocks are first loosened, then the bolts 12^a rotated so as to move the bars 12 inwardly. Bolts 13^a, 70 which move the bars 13 inwardly and outwardly, may be turned to clamp and unclamp casting 4.

75 I do not claim in this application the mechanism for adjusting the screen as described above, as this forms the subject matter of a divisional application filed by me October 29, '10, and numbered 589,827.

90 Preferably, the bars 12 which control the position of the screen, have no connection with the ring bars which are used for adjusting the grinding surface, but they form segments thereof, being mounted in the concentric grooves 1^a inside the casing containing said grinding surface. The rings 95 for adjusting the grinding surface bars are oppositely inclined on their adjacent edges, and are movable inwardly and outwardly by means of bolts, in the same manner as the bars 12 and 13. The grinding surface 100 is practically composed of bars 14 having 105

serrations on their inner faces, the ends of said bars being oppositely beveled, as shown in Figs. 2 and 3. The outer rings 15 are made adjustable inwardly and outwardly by means of bolts 15^a, while the inner rings 16 are made adjustable inwardly and outwardly by means of bolts 16^a. By moving the outer rings inwardly and the inner rings outwardly, the bars are adjusted toward the beaters, the opposite adjustment of said rings effecting the outward adjustment of said bars. The grinding surface bars preferably terminate under flanges of casting 4, a space being provided beyond each end bar whereby, when the grinding surface is adjusted inwardly to take up wear, the diminishing circle will cause the end bars to move in under the flanges of the casting 4.

20 Ordinarily the grinding surface, when the beaters are new and the points not worn, is positioned with the rings 16 in their innermost position and the rings 15 in their outermost position. As the beaters wear, 25 the rings 15 are adjusted inwardly after retracting the rings 16. The retracting movement of the rings 16 controls the adjustment of the grinding surface, which, it will be observed, by moving the rings 15 and 16 in opposite directions, is effected in 30 a positive manner both toward and from the beaters.

In order to positively move rings 15 and 16 inwardly, so as to make it unnecessary 35 to rely upon the inward movement of companion ring for effecting such adjustment, I provide set screws 15^b and 16^b, which preferably alternate with the bolts 15^a and 16^a. By this construction, when it is desired to 40 adjust either ring 15 or 16 outwardly, the set screws 15^b and 16^b are loosened the proper distance, and then the bolts 15^a and 16^a tightened so as to draw the ring outwardly against the set screws. When it is 45 desired to adjust the rings 15 or 16 inwardly, the bolts 15^a and 16^a are first loosened and then the set screws tightened up. The set screws 15^b and 16^b are preferably threaded in the casting, while the bolts 15^a and 50 16^a are threaded in the rings and pass loosely through the casting.

A strap or band 17 is arranged under the 55 grinding surface at approximately the middle portion of the bars to support the same, and this strap, which is sufficiently flexible to conform to the various adjustments of the grinding surface, has its ends supported by threaded rods 18 whose ends pass through the casting 1 and receive nuts for adjusting 60 said strap.

19 is a shaft mounted in suitable bearings arranged in extensions projecting from the sides of casting 1, which extensions are covered by cap plates 20 bearing the partition 65 walls provided in the extensions, which, with

the cap plates, constitute an oil receptacle for lubricating the shaft in its bearings, by means of the usual slip rings. A screw 21 is provided to align the shaft bearings. A driving pulley 22 is arranged on the end of the shaft, and if desired, a balance wheel can be arranged on the opposite end of said shaft.

Within the casting 1, the shaft has head plates provided with fan blades 23, which 75 tend to draw in air and material from each side of the machine and force the same toward the center of its zone of beaters. The material is fed into the "eye" of the machine around the shaft at each side through 80 conduits 24, which conduits terminate at the extensions and adjacent to the partition walls thereof which form the oil receptacle. These conduits lead from under a feeding mechanism comprising a pocket cylinder 25 85 arranged in a suitable casing at the lower end of a discharge pipe 26. An adjustable wall 27 in said casing determines the amount of material passing beyond the cylinder 25. When the wall is close to the cylinder 21, 90 only the material which can enter the pocket is fed to the machine, whereas, by adjusting the wall 27 outwardly, an additional quantity of material will be fed to the machine. The outer end of the shaft of the pocket 95 cylinder is provided with a ratchet 28, with which cooperates a pawl 29 carried by an arm 30 provided with a T-groove, in which is adjustably mounted one end of an eccentric link 31. An eccentric 32, with its usual 100 strap, to which link 31 is connected, is mounted on a counter shaft 33, whose pulley 34 is driven by a belt 35 fastened around a pulley 36. A conjoined pulley 37 is driven by belt 38 which passes over shaft 19.

39 is a pocket or receptacle arranged directly under the pocket feed cylinder for the purpose of catching particles of iron or other foreign material too heavy for the air entering through dampers 40, arranged at 110 the end of said receptacle, to carry into the machine. Auxiliary air supply pipes 41, controlled by dampers 42, lead into the feed openings at the "eye" of the machine on each side, for the purpose of affording better control of the amount of material fed into the machine. These auxiliary air supply pipes 42 lead from the bottom of the machine and tend to keep the same clear from dust or pulverized material escaping 120 through the cracks in the bars of the grinding surface and which might tend to accumulate under the grinding surface. The space under the grinding surface forms a receptacle for catching material in the manner described, and is therefore preferably housed in, but, as shown in Fig. 1, this space 125 communicates with the exterior around the flanged ring 6. By this construction, air drawn through the pipes 41 passes down 130

wardly around the bars of the grinding surface and draws all flying particles of dust escaping therefrom back into the machine, whence it will be discharged through the 5 pipe 10.

Beaters 43, which coöperate with the grinding surface and act upon the material in the machine to reduce the same to pulverulent form, are preferably constructed by

- 10 giving to said beaters a quarter turn, whereby the major axis of their outer ends lies substantially parallel to shaft 19. In this manner these beaters act as paddles. The outer flat ends of the beaters are curved 15 forward and provided with cutting edges, which are preferably sharpened. The beaters are mounted between supporting disks 45, and have extensions 43^a which coöperate with the hubs of said disks to prevent 20 the beaters from falling forward, when the machine is at rest, and dulling their edges. These extensions do not interfere with the rearward yielding movement of the beaters in operation.

25 The operation of the machine in reducing material to powdered form is as follows: The material to be reduced is supplied to the feed pipe 26 and fed in predetermined quantities to the machine. The machine being in 30 operation, fan blades 23 serve to draw the material, with air, into the machine, through the feed openings around the shaft 19, said feed openings acting in this particular like the eyes of a fan. Fan blades 23 tend to 35 throw the material toward the center of the zone of revolving beaters. Centrifugal force tends to throw the material outwardly against the grinding surface. The curved flat blades of the beaters tend to pick up the 40 material from the grinding surface by a scooping action and return the material toward the center of the machine in opposition to the direction in which the material is inclined to move under centrifugal force.

45 The material is thus reduced, not only by contacting with the grinding surface and the beaters, but by attrition, the oppositely moving particles rubbing against each other, so that ultimately they are of sufficient fineness to be passed through the screen and into 50 the discharge pipe 10, which is preferably connected to an exhaust fan. The passage of the material through the screen and the action of the beaters in tending to wipe the 55 material off this screen, is similar to that of the well known Griffin mill, the fine particles of material being bolted diagonally.

I am aware that minor changes in the construction, arrangement and combination 60 of the various parts of my device can be made and substituted for those herein shown and described without departing from the nature and spirit of my invention.

I do not claim the construction and arrangement of the hammers or beaters, the

side feed, the feeding mechanism, or the manner of controlling the supply or exhaustion of air to effect the discharge of material from the machine, as the same is the invention of Milton F. Williams, and 70 forms the subject matter of a companion application filed of even date herewith.

I claim:—

1. In a pulverizer, the combination of a 75 casing, a grinding surface arranged therein comprising sections, means for supporting each section comprising a member engaging the top of said section, means for adjusting said member, an independent member engaging the bottom of said section, and means 80 for adjusting said last mentioned member, said adjusting means being adapted to adjust the section toward and from the center of the casing and to clamp said section in adjusted position.

2. In a pulverizer, the combination of a 85 casing, a grinding surface arranged therein, comprising sections, means for supporting each section comprising a member having a beveled side engaging the top of the section, 90 means for adjusting said member, an independent member having a beveled side engaging the bottom of the section, and means for adjusting said member, said adjusting means being adapted to adjust the section 95 toward and from the center of the casing and to clamp said section in adjusted position.

3. In a pulverizer, the combination of a 100 casing, a grinding surface arranged therein comprising sections, means for supporting each section comprising coöperating beveled members arranged on opposite sides of said section, said beveled members engaging the top and bottom respectively of the section to 105 clamp it in position.

4. In a pulverizer, the combination of a 110 casing, a grinding surface arranged therein comprising sections, means for supporting each section comprising coöperating beveled members arranged on opposite sides of said section, said beveled members engaging the top and bottom respectively of the section to clamp it in position, and means for independently adjusting each of said beveled 115 members.

5. In a pulverizer, the combination of a 120 casing, a grinding surface arranged therein having sections, means for supporting each section comprising a beveled member engaging the section on the top thereof at both sides, means for adjusting said members toward and from each other, additional beveled members engaging the section on both sides of the bottom thereof, and means 125 for adjusting said latter members toward and from each other.

6. In a pulverizer, the combination of a 130 segmental grinding surface, curved rings having oppositely inclined beveled edges en-

gaging the top and bottom respectively of said surface so as to clamp the same in place.

7. In a pulverizer, the combination of a 5 segmental grinding surface, curved rings having oppositely inclined beveled edges engaging the top and bottom respectively of said surface so as to clamp the same in place, and means for adjusting said rings inwardly and outwardly to change the position of the 10 grinding surface.

8. In a pulverizer, the combination of a segmental grinding surface, two curved rings engaging said surface at each side on 15 the bottom thereof, and two coöperating curved rings engaging said surface at either side at the top thereof, said surface being clamped between the adjacent rings.

9. In a pulverizer, the combination of a 20 segmental grinding surface, curved rings having beveled edges engaging the surface on each side at the bottom thereof, coöperating curved rings with oppositely inclined beveled edges engaging the surface at the 25 top thereof, and means for independently adjusting said rings inwardly and outwardly.

10. In a pulverizer, the combination of a segmental grinding surface, a casing in 30 which said surface is mounted, means for supporting said surface within the casing comprising a member having a beveled surface supported by the casing and adapted to engage the grinding surface at one side thereof, means for adjusting said member inwardly and outwardly on the casing, a member having a beveled surface engaging the opposite side of the grinding surface and supported by the casing, and means for 40 adjusting said member inwardly and outwardly.

11. In a pulverizer, the combination of a 45 grinding surface composed of separate sections, curved bars having beveled edges for coöperating with the ends of said sections, means for adjusting said bars inwardly and outwardly to adjust the sections with respect to the casing, and an adjustable strap arranged under the centers of said bars.

12. In a pulverizer, the combination of a 50 segmental grinding surface, curved rings having oppositely inclined beveled edges engaging opposite sides of the segments of said grinding surface, and set screws for positively moving said rings inwardly.

13. In a pulverizer, the combination of a 55 segmental grinding surface, curved rings having oppositely inclined beveled edges engaging opposite sides of the segments of said grinding surface, and bolts for positively moving said rings outwardly.

14. In a pulverizer, the combination of a 60 segmental grinding surface, curved rings having oppositely inclined beveled edges en-

gaging opposite sides of the segments of said grinding surface, set screws for bearing against said rings for moving the same inwardly, and bolts threaded into said rings for moving the same outwardly.

15. In a pulverizer the combination with a 70 grinding cage capable of being circumferentially contracted and expanded, of means for expanding or contracting said cage, which means comprises a pair of independently movable rings engaging the ends of 75 the grinding cage and means for adjusting the positions of said rings.

16. In a pulverizer the combination with a segmental grinding cage capable of being circumferentially expanded or contracted, of 80 means for expanding and contracting said cage, which means comprises a pair of independently adjustable rings engaging the ends of the cage and an adjustable strap for supporting the central portion of said cage 85 in its adjusted position.

17. In a device of the character described, the combination of a casing having a grinding surface with a discharge opening, a screen covering said discharge opening, a frame supporting said screen in position, and means on each side of said frame for adjusting the same relative to the casing. 90

18. In a device of the character described, the combination of a casing having a grinding surface with a discharge opening, a screen covering said discharge opening, a frame for supporting said screen in position, means on each side of said frame for adjusting the same relative to the casing, 95 and means for clamping the frame in adjusted position. 100

19. In a device of the character described, the combination of a casing having a grinding surface provided with an opening, a 105 screen fitted within the opening, means for adjusting the same relative to the casing, and means for clamping the screen upon said adjusting means.

20. In a device of the character described, the combination of a casing having a grinding surface provided with an opening, a screen adjustably mounted therein, means on opposite sides of the screen for adjusting same relative to the casing, and means also 115 on opposite sides of the screen for holding the same against said adjusted means.

21. In a device of the character described, the combination of a casing having a grinding surface provided with an opening, a 120 screen arranged in the opening, and a movable member having an inclined surface for adjusting said screen relative to the casing.

22. In a device of the character described, the combination of a casing having a grinding surface provided with an opening, a screen arranged therein, a bar having a beveled edge coöperating with said screen, and 125

means for adjusting the bar relative to said casing.

23. In a device of the character described, the combination of a casing having a grinding surface provided with a discharge opening, a screen covering said discharge opening, a frame for supporting said screen in position, having beveled faced ribs attached, and means on each side of said frame for

engaging the beveled faces to adjust the same relative to the casing.

In testimony whereof I hereunto affix my signature in the presence of two witnesses, this 2nd day of June, 1910.

EDWARD H. FRICKEY.
